ROTARY IMPACT HAND TOOL

Reginald J. Aspeek, Utica, Mich.

Application January 8, 1957, Serial No. 633,107

3 Claims. (Cl. 81—52.3)

This invention relates to a hand tool and more particularly to a self-contained hand tool for tightening or loosening screws, bolts, nuts or the like by the translation of the impact force of an axially movable mass into a rotational force.

The prior art discloses a number of axial impact screw driver or wrench-type hand tools which require the use of two hands in their operation. That is, they must be held by one hand while the other hand wields a hammer, the momentum of the mass of the head of which is appropriately translated through the impact tool into the desired threading or unthreading rotational movement. It is an object of the present invention to provide a self-contained tool which does not derive its impact force through an auxiliary implement such as a separately wielded hammer head.

In its preferred form the axial impact tool comprises an elongated stem encompassed by a tubular ram member slidably and rotatably journalled on the upper portion of said stem. The tubular ram member carries at its upper end a heavy handle mass. At its lower end, the tubular ram member is provided with axially depending helical lobes. Secured to the lower end of said stem is a tool bit adaptor having axially extending lobes on the upper end thereof. The ram member lobes and the tool bit adaptor lobes are normally in spaced axial relationship to each other, the tubular ram member being maintained in retracted position by a compression spring. A means is provided which is effective to maintain the tubular ram member in pre-selected position on the stem whereby the ram member lobes are in a predetermined relationship to the tool bit adaptor lobes when said lobes are axially spaced from one another. The predetermined radial relationship is utilized to predetermine the direction of rotation of the tool bit adaptor upon the handle mass being driven downwardly to cause impact engagement of said opposed lobes such as will cause rotation of the tool bit adaptor.

Further objects and advantages and the features of construction embodied in the present invention will be apparent from the following description and appended claims, reference being had to the accompanying drawing forming a part of this specification wherein like reference numerals designate corresponding parts in the several views.

Fig. 1 is a sectional elevation of a tool fitted with an adaptor and a screw driver bit.

Fig. 2 is a section view taken substantially through the line 2—2 in Fig. 1 looking in the direction of the arrows.

Before explaining in detail the present invention, it is to be understood that the invention is not limited in its application to the details of construction and arrangement of parts illustrated in the accompanying drawing, since the invention is capable of other embodiments and of being practiced or carried out in various ways.

In the drawing there is illustrated, by way of example, a preferred embodiment of the impact tool, generally

2

designated 10. The tool 10 comprises a square cross-section elongated shaft or stem 11. Slidably mounted on the shaft or stem 11 is a tubular ram member 12. In its retracted position, as shown in Fig. 1, the ram member 12 extends substantially above the upper end of the shaft or stem 11. Contained within the hollow portion of the ram member 12 is a compression spring 13 adapted to restore and maintain the tubular ram member in its inoperative retracted position. The spring 13 reacts between the upper end 14 of the stem 11 and a threaded plug 15 closing the upper end of the chamber in the tubular ram member 12.

The upper end of the tubular ram member 12 carries a heavy handle mass 16 which may be cast iron molded to substantially the elliptical contour illustrated. It is an important feature of the present invention that it be understood that this handle mass 16 is a connected or integral part of the tubular ram member 12. The lower end of the tubular ram member is provided with two helical lobes 17, the apexes of which are 180° apart.

It will be noted that the central hole 18 of the tubular ram member 12 is circular in cross-section. The ram member is thus freely rotatable about the stem 11. A positioning means is provided to releasably maintain the ram member 12 in pre-selected positions relative to the stem 11. Referring to Fig. 2, the tubular ram member 12 is provided with a pair of diametrically opposed pins 19. The pins 19 are yieldingly maintained in engagement with the stem faces by means of a steel spring band or circular clip 20 exteriorly embracing the tubular ram member. Also carried on the exterior of the tubular ram member 12 is a sleeve 21 which may be slidably moved downwardly over the band or clip 20. When so positioned, the pins 19 are firmly held against outward movement and lock the tubular ram member 12 and the stem 11 against relative rotational movement.

The lower end of the stem 11 has secured thereto a tool bit adaptor 22 provided with a pair of helical lobes 23 on the upper end thereof. The apexes of the lobes 23 are also spaced 180° apart, as were the apexes of the lobes 17 on the lower end of the tubular ram member 12.

It will be noted that the apexes of the one set of lobes 17 are displaced relatively to the apexes of the other set of lobes 23. This displacement is preferably 45° circular degrees. This relative displacement is always maintained through the control that the pins 19 exert on the positioning of the tubular ram member 12 on the shaft or stem 11. The diametrical axis of the pins 19 is so positioned relative to the location of the apexes of the lobes 17 that the latter are always maintained at a 45° displacement relative to the apexes of the lobes 23 which are in fixed relationship to the shaft or stem 11.

The tool bit adaptor 22 may be of any conventional type adapted to non-rotatably hold a tool such as a screw driver bit 24.

Impact tools are particularly useful for starting screws, bolts, nuts or the like which resist turning movement by an ordinary tool because of damaged threads or because they have become frozen in position by corrosion. To dislodge such a screw, bolt, nut or the like with the impact tool embodying the present invention, it is only necessary to position the lobes 17 on the tubular ram member 12 relative to the lobes 23 so that the tool bit will be rotated in the proper direction. As shown in Fig. 1, engagement of the lobes 17 with the lobes 23 will result in the tool bit being rotated in a counterclockwise direction. Should it be desired to have the tool bit 24 rotate in a clockwise direction, it is only necessary to rotate the tubular ram member 12 ninety degrees in either direction relative to the stem 11. The spring clip 20 will permit the pins 19 to move outwardly a sufficient distance so that the tubular ram member 12 may be ro-

60
65
70

tated relative to the stem 11. As soon as the pins 19 pass the square corners of the stem, they will snap back into position so as to align the lobes 17 in proper relationship to the lobes 23.

The tool having been set so that the tool bit will be turned in the proper direction, the head 25 of the tool bit is then engaged with the object to be loosened. The handle portion or mass 16 is then grasped and manually driven downwardly. The momentum of the mass 16 will be transmitted through the tubular ram member 12 to the adaptor 22. Because of the helical relationship of the lobes 17 to the lobes 23, a component of the impact force will tend to cause the adaptor to rotate. Inasmuch as the adaptor is rigidly secured to the end of the stem 11, the stem 11 will also tend to be rotated relatively to the tubular ram member 12. The pins 19 will permit this since they will be driven outwardly against the tension of the spring clip 20. However, the degree of travel caused by the helical relationship of the lobes is such that the relative rotation caused is less than 90° and it will not be necessary to reset the tool in order to repeat the impact movement.

The tool embodying the present invention has the particular advantage that the weight mass 16 is a part of the tool. Therefore, only one hand is needed to manipulate the tool. This is a highly desirable characteristic when the tool is to be used under conditions where there is insufficient room to swing a hammer.

After the object to be unthreaded has been loosened, it is only necessary to drop the sleeve 21 down over the spring clip 20 thereby locking the tubular ram member 12 to the stem 11 and the tool may then be used as a conventional device to complete the removal of the threaded object.

I claim:

1. An axial impact type rotary tool comprising an elongated stem at least a portion of which is of square cross-section, a tubular ram member slidably and rotatably journaled on the upper portion of said stem, an integral heavy handle mass carried on the upper end of said ram member, the lower end of said ram member being provided with a pair of axially depending diametrically positioned helical lobes, a tool bit adaptor having a pair of axially upwardly extending diametrically positioned helical lobes on the upper end thereof, said pairs of lobes being normally in axially spaced relationship to each other, and positioning means effective to maintain said ram member in a pre-selected position on said stem whereby the apexes of the ram lobes are normally radially displaced on one side or the other of the apexes of the tool bit adaptor lobes, said radial relationship determining the direction of rotation of the tool bit adaptor upon the handle mass being driven downwardly to cause impact engagement of said opposed lobes such as will result in rotation of the tool bit adaptor, said positioning means comprising diametrically opposite pins carried in said ram member radially engaged with opposite faces of the stem square portion, and spring means encircling said ram member normally yieldingly maintaining said pins in stem engaging position.

2. An axial impact type rotary tool comprising an elongated stem at least a portion of which is of square cross-section, a tubular ram member slidably and rotatably journaled on the upper portion of said stem, an integral heavy handle mass carried on the upper end of said ram member, the lower end of said ram member being provided with a pair of axially depending diametrically positioned helical lobes, a tool bit adaptor having a pair of axially upwardly extending diametrically

positioned helical lobes on the upper end thereof, said pairs of lobes being normally in axially spaced relationship to each other, positioning means effective to maintain said ram member in a pre-selected position on said stem whereby the apexes of the ram lobes are normally radially displaced on one side or the other of the apexes of the tool bit adaptor lobes, said radial relationship determining the direction of rotation of the tool bit adaptor upon the handle mass being driven downwardly to cause impact engagement of said opposed lobes such as will result in rotation of the tool bit adaptor, and spring means contained within said ram member and compressed against the upper end of said stem to retract the same after completion of the impact stroke, said positioning means comprising diametrically opposite pins carried in said ram member radially engaged with opposite faces of the stem square portion, spring means encircling said ram member normally yieldingly maintaining said pins in stem engaging position, and a sleeve encircling said ram member and positionable over said spring means to non-yieldingly maintain said pins in stem engaging position.

3. An axial impact type rotary tool for turning a threaded object, comprising an elongated stem at least a portion of which is of square cross-section, a tubular ram member slidably and rotatably journaled on the upper portion of said stem, an integral heavy handle mass carried on the upper end of said ram member, the lower end of said ram member being provided with a pair of axially depending diametrically positioned helical lobes, a tool bit adaptor having a pair of axially upwardly extending diametrically positioned helical lobes on the upper end thereof, said pairs of lobes being normally in axially spaced relationship to each other, positioning means effective to maintain said ram member in a pre-selected position on said stem whereby the apexes of the ram lobes are normally radially displaced on one side or the other of the apexes of the tool bit adaptor lobes, said radial relationship determining the direction of rotation of the tool bit adaptor upon the handle mass being driven downwardly to cause impact engagement of said opposed lobes such as will result in rotation of the tool bit adaptor, spring means contained within said ram member and compressed against the upper end of said stem to retract the same after completion of the impact stroke, and sleeve means positionable to block such movement of said pin means as would permit relative rotational movement of the ram member about said stem, said positioning means comprising diametrically opposite pins carried in said ram member radially engaged with opposite faces of the stem square portion, spring means encircling said ram member normally yieldingly maintaining said pins in stem engaging position, and a sleeve encircling said ram member and positionable over said spring means to non-yieldingly maintain said pins in stem engaging position.
